CONVEYER

Herman Seubert, Franklin Park, Ill., assignor to
The Petersen Oven Company, Chicago, Ill., a
corporation of Illinois

Application February 17, 1942, Serial No. 431,214

16 Claims. (Cl. 198—108)

This invention relates to conveyers of the type including a plurality of material supporting devices or trays, and more particularly to conveyers of the class wherein the load supporting surface of the material supporting devices or trays is caused to remain in a substantially horizontal position throughout its entire path of travel around the conveyer.

Conveyers of this general type are adapted to a relatively wide field of use and are particularly suitable for use in connection with commercial baking ovens of the type which are constructed and arranged so that foodstuffs may be loaded onto and off of the conveyer at the same end.

Conveyers of the type employing transversely spaced apart continuous strands of flexible chain on which are carried material supporting devices have been extensively used in connection with baking ovens. Such types of conveyer structures, however, have been of great concern to bakers because of the vibration inherent in the conveyer chains as a result of the movement of the chains around end sprocket wheels; and furthermore, because the material supporting devices, particularly in single cycle operated oven conveyers where material is loaded and unloaded at the same point, are generally pivoted adjacent their upper end, which results in the devices having imparted thereto a swaying and jiggling motion as they move from one run of the conveyer to the other run. Frequently such conditions become aggravated due to improper positioning of pans of foodstuffs on the material supporting devices and which condition tends to cause the body of the foodstuff to shift toward one end or side of the pan. Such movements result in non-uniformity of shape, thickness, coloring or browning of the baked foodstuff.

One of the primary objects of this invention is to provide a novel and improved form of conveyer construction characterized by the provision of a plurality of independent material supporting devices adapted to be moved into abutting relation with each other in such a manner as to impart movement from one to another and thereby effect movement of all of the devices along the runs of the conveyer in a continuous manner.

Another object is to provide an improved conveyer structure of the character indicated comprising a plurality of independent material supporting devices wherein said devices are each constructed in relatively flat form, and provided with rollers at its opposite ends for support in guideways, together with novel transferring means for causing each material supporting device to be handled individually in movement from one run of the conveyer to the other.

A further object is to provide an improved conveyer of the class indicated comprising a plurality of independent material supporting devices

and transferring means at opposite ends of the conveyer for individually transferring said devices from one run of the conveyer to the other, together with control means associated with the respective transfer means for maintaining said devices in a horizontal position during the period of transfer from one run of the conveyer to the other.

Still another object of this invention is to provide a novel and improved conveyer structure of the class indicated which is relatively simple in construction, durable in operation and economical to manufacture.

Other objects and advantages of this invention will be apparent from the following description taken in connection with the accompanying drawings, in which:

Figure 1 is a vertical longitudinal sectional view through a baking oven showing the general arrangement of the novel conveyer construction embodying the present invention;

Figure 2 is a horizontal sectional view through the oven, taken substantially as indicated at line 2—2 of Figure 1, showing the novel conveyer construction in plan view;

Figure 3 is an enlarged fragmentary vertical sectional view through one end of the conveyer taken substantially as indicated at line 3—3 of Figure 2;

Figure 4 is a view similar to Figure 3 showing one of the material supporting devices in a position preparatory to transfer from the lower run of the conveyer to the upper run of the conveyer;

Figures 5 and 6 are transverse vertical sectional views, taken substantially as indicated at lines 5—5 and 6—6, respectively, on Figure 3;

Figure 7 is a fragmentary vertical sectional view through portions of two adjacent material supporting devices and taken substantially as indicated at line 7—7 on Figure 2;

Figure 8 is a fragmentary vertical section through one side of the upper and lower runs of the conveyer, taken substantially as indicated at line 8—8 on Figure 1, and showing removable grill form supporting trays mounted within the frames of the material supporting devices;

Figure 9 is a transverse vertical sectional view through one of the material supporting devices, with the grill tray therein, taken substantially as indicated at line 9—9 on Figure 8;

Figure 10 is a fragmentary perspective view of a wall of the oven showing the terminal portions of the guideways for the upper run of the conveyer, and

Figure 11 is a plan elevational view of one end portion of a material supporting device, with the grill tray in position therein.

In the drawings I have shown my novel form of conveyer construction as used in conjunction with the baking chamber of a commercial type

of baking oven of conventional form and as designated generally at 10. The oven as illustrated is of the low height type, provided at one end with a door 11 through which the conveyer is loaded and unloaded. Inasmuch as the oven per se constitutes no part of the present invention, it is believed unnecessary to refer to details of construction and arrangement thereof.

The conveyer constituting the present invention is made up of a plurality of separate, independent material supporting devices, indicated generally at 15, which are disposed in endwise abutting relation to each other, by virtue of which movement of one is imparted to the next adjacent device and by virtue of which all of the devices on the respective separate runs of the conveyer are moved as a unit, as a continuously moving conveyer. The conveyer as seen in the drawings is of the horizontally traveling type and includes upper and lower runs which, for convenience, will be designated as A and B, respectively.

Suitable guide means is provided for the opposite ends of the material supporting devices for both upper and lower runs of the conveyer. The guide means throughout the major portion of the horizontal runs is in the form of a channel guideway or trough, and, as may be seen in Figure 8, the guide means for the upper run includes a pair of angle members 17 and 18, and the guide means for the lower run includes a pair of angle members 19 and 20.

Mounted in registration with the guideways formed by the channels for the respective upper and lower runs, at each end thereof, is a curved end track member 22, as clearly seen in Figures 3 to 5 of the drawings. These members 22 are spaced from the side walls of the baking chamber so as to be in a position to be engaged by rollers of the material supporting devices, as will hereinafter be described.

The material supporting devices 15 each include a generally rectangular shape frame 24 composed of end bars 25 connected together by cross bars or tie members 26. Mounted on each of the end bars 25 and projecting outwardly therefrom are a series of uniformly spaced apart, horizontally aligned rollers 28, journaled in a conventional manner on pins 29. The rollers at the respective outer ends of the end plates 25 have mounted coaxially therewith auxiliary rollers 30, which are of the same size as the other rollers 28, as clearly seen in Figure 11. The spacing between adjacent rollers corresponds to the pitch of the sprocket wheels employed for moving said material supporting devices, as will hereinafter be described.

A corresponding cross bar 26 of each material supporting device is provided with a pair of socket fixtures 32 adjacent opposite ends, as seen in Figure 2 of the drawings, and threaded in each of the sockets 32 is a headed bumper member 33. The ends of the bumper members 33, as seen in Figure 2 of the drawings, are adapted to abut against the adjacent cross members 25 of the next material supporting device and serve as the medium for transmitting of forces for moving the devices, one by another. The bumper members 33 provide for nicety of adjustment and insure proper spacing of the material supporting devices with each other so that the adjacent sets of rollers 28 and 30 of two consecutive devices are spaced apart a distance substantially equal to the pitch of the sprocket wheel above

referred to, and to insure proper positioning of the members 33, a lock nut 34, is employed.

It will be apparent that the material supporting devices may be fabricated in any desired and suitable manner. In the form shown in the drawings, the rectangular frame 24 permits the use of a removable grill structure designated at 35, which grill structure is composed of a plurality of transversely spaced apart parallel rods 36 supported at their ends in the vertical leg of an angle shaped member 31, the horizontal legs of which angle members are adapted to seat upon the transverse tie members 26, as clearly seen in Figure 9. Thus, the grill structure may be quickly and easily removed for repair or replacement, and otherwise remains relatively stable in seated position in the frame of the material supporting device 15.

Transferring means of identical form are located at the opposite ends of the conveyer for transferring the material supporting devices individually from one run of the conveyer to the other. The transferring means, as will herein-after appear, is so constructed and arranged as to permit proper functioning of the conveyer when operating in either direction of travel. In so far as it is practical, one of the transferring means will be described in detail and it may be understood to be descriptive of the other except where otherwise indicated.

Rigidly mounted on a main operating shaft 40, extending transversely of the oven chamber, as seen in Figure 2, are a pair of transversely spaced apart main sprocket wheels 41, spaced in proper relation to the walls of the chamber and the guideways so as to engage and drive all of the rollers 28 on the respective material supporting devices, as may be clearly seen from Figures 3 and 6 of the drawings. Disposed outwardly in endwise direction and in offset relation to the main sprocket wheels 41 are auxiliary sprocket wheels 43, as may be seen by a comparison of Figures 5 and 6 of the drawings, in a position to cooperate only with the auxiliary rollers 30, located at the leading edge of the material supporting devices. Said auxiliary sprocket wheels are each rigidly mounted upon stub shafts 44 extending through the walls of the oven. The stub shafts 44 exteriorly of the oven are interconnected by chain drives, as indicated at 46, with the adjacent operating shaft 40 so that the respective pairs of auxiliary and main sprocket wheels are driven in proper synchronized relation to each other. It is to be understood that the main operating shafts 40 and stub shafts 44 are suitably journaled within the walls of the oven (not shown), or as may be desired on either the interior or exterior of the wall of the oven. As seen in the drawings, the main operating shaft 40, located at the right hand end of the conveyer, as seen in Figure 2 of the drawings, is provided with an extension 40a for connection to a suitable source of power. It is also to be understood that either of the operating shafts 40 might properly be connected to a source of power inasmuch as the conveyer operates satisfactorily in either direction of travel. In the arrangement shown the main and auxiliary sprockets at the left hand end of the conveyer, as seen in Figure 2, are driven by abutment of the rollers of the material supporting devices 15, therewith.

The reason that the auxiliary sprocket wheels 43 are mounted on stub shafts is to enable movement of the material supporting devices across

the inner face thereof, such as may be seen in Figures 3 and 5 of the drawings.

Associated with each set of main and auxiliary sprocket wheels at each side of the conveyer and at each end thereof is a control device, as indicated at 50, which is pivotally mounted at 51 to the side wall of the oven chamber. The control device includes a control arm 53 disposed laterally outside of the auxiliary sprocket wheel 43, as seen in Figures 3 and 5 of the drawings, in a position to be moved into the path of travel of the auxiliary rollers 30 at the leading edge of the material supporting devices during transfer from one run of the conveyer to the other. The upper end of the arm 53 is angled off, as indicated at 54, so as to cause the arm to be conveniently depressed upon engagement by one of the auxiliary rollers 30 when the material supporting device is moving from the upper run of the conveyer to the lower run of the conveyer, as would be the case at the left hand end of the conveyer, as seen in Figure 1, in view of the direction of travel indicated in Figures 3 and 4.

The control members 50 each include a cam surface 56 adapted to be normally disposed in the path of travel of the auxiliary rollers 30 of the material supporting devices, and the shape of cam 56 follows the same arcuate contour as the roller engaging surface of the end track members 22. As a material supporting tray 15 moves along the lower run of the conveyer, the auxiliary rollers 30 engage the cam surfaces 56 of the respective control members 50 and tend to ride up said cam surfaces 56, which action depresses the cam members 50 so as to rotate them about their pivots 51, so that the material supporting device may continue its forward movement along the angle tracks 20 until said auxiliary rollers at the leading edge of the device 15 engage the inner surface of the end track members 22. It is to be understood that as the auxiliary rollers at the leading edge of the material supporting device engage the cams 56, said members 50 are rocked upwardly, so that the arms 53 swing counterclockwise, and it is to be understood that said arms are free to so move because the previous material supporting device being transferred will be out of the way. After the auxiliary rollers at the leading edge of the material supporting device pass over the cams 56, said cams are again restored to the position seen in Figure 4 so that the upper contours of arms 53 are disposed substantially in aligned relation to the contour of a portion of the inner roller engaging surface of the end track members 22. As the rollers 28, at the leading edge of the material supporting device engage the end track members 22, and cause said device to move upwardly, the auxiliary rollers 30 at said end are positively engaged and driven by the auxiliary sprocket wheels 43. During the initial portion of such driving movement of the material supporting device, said auxiliary rollers at the leading end of the device engage the arms 53 of the control members to prevent upward movement thereof until said auxiliary rollers pass beyond the end of the arms and during which time the members 50 are held fixed, and the auxiliary rollers 30 at the following edge of the material supporting device are caused to ride upwardly on the cams 56 in the same relation as the forward or leading edge of the material supporting device is elevated. Such upward movement of the material supporting devices is accomplished by the main sprocket wheels 41 which, as above mentioned, engage all of the rollers 28 of each

material supporting device. The cams 56, while the arms 53 are held down, thus tend to cause the rollers at the following edge of the material supporting device to remain seated in the sockets of the main sprocket wheels 41 until the said main sprocket wheels can positively support said following edge of the device 15. In the meantime, the auxiliary rollers 30 at the leading edge of the device 15 are in driving engagement with the auxiliary sprocket wheels 43, and because the main sprocket wheel 41 and auxiliary sprocket wheels 43 are driven in synchronized rotation the material supporting device is thus moved from the lower run of the conveyer to the upper run of the conveyer, and during which period of movement said material supporting device 15 is caused to remain in a horizontal position, as seen in Figure 3 of the drawings. When the device 15 is elevated so that its rollers are in alignment with the channels of the upper guideway formed by channels 17 and 18, the driving motion of the sprocket wheels moves the device into abutting relation to the previously moved device and thus serves to impart a continuous movement to all of the devices on both runs of the conveyer. It will be apparent that after the device 15 is in alignment with the channels 17 and 18, it is moved forwardly therealong by the sprocket wheels 41 and 43, and during such movement the next succeeding device is being raised by the sprocket wheels and moved into synchronized abutting engagement with the preceding device so that the movement of the devices on the respective runs of the conveyer is smooth and continuous.

As may be clearly seen in Figure 10 of the drawings, the angle member 18 forming the lower portion of the upper runway is notched at 18a to provide clearance for the auxiliary rollers 30 and their adjacent rollers 28 during their vertical movement until they register with the channel guideway constituting the upper runway of the conveyer. The lower angle member 18 of the upper guideway is also notched, as indicated at 18b and 18c, for accommodating the upper portion of the respective main and auxiliary sprocket wheels, as may be clearly seen in the drawings.

The control members 50 at the left hand end of the conveyer, as seen in Figure 1, functions in a manner opposite to that above described. In other words, as the material supporting device moves downwardly under support and control of the main and auxiliary sprocket wheels, together with the end track member 22, the auxiliary rollers at the leading end of the device 15 engage arms 53 and depress them to align with the contour of the inner surface of the end track members 22 and hold the members 50 in fixed position until the material supporting device rides forwardly on the lower run of the conveyer. During such downward movement the auxiliary rollers 30 at the opposite end of the device are guided and supported on the then fixed cams 56 as the weight of the adjacent end of the device is gradually released from the main sprocket wheels 41; and, as the device 15 becomes deposited on the lower runway, the main and auxiliary sprocket wheels 42 and 43, respectively, drive it forwardly, relieving the pressure on the arm 53, and when the auxiliary roller 30 at the following end of the device rides over the hump 56a of the cams 56, the arms 53 are temporarily moved upwardly merely to accommodate continuous forward movement of the device 15 without obstruction. Each of the control members 50 is provided with a counter-

weight 61 which tends to return the control members to the position seen in Figure 4 of the drawings.

The upper angle member 19 of the lower runway terminates at opposite ends adjacent the axes of the main sprocket wheels, as seen in Figure 4 of the drawings, so as to provide clearance for the material supporting devices when moving into or out of the lower runway.

Because the sprocket wheels and the material supporting devices with the rollers properly located are so designed that the end rollers of two adjacent devices are engaged in consecutive pockets, between the teeth of the sprocket wheels, and because of the timed synchronous relation of the main and auxiliary sprocket wheels, it will be apparent that the material supporting devices in being transferred from one run to the other are brought into timed abutting engagement with previously transferred devices in such a manner as not to impart shock or appreciable vibration to the other devices, and effect a smooth engagement so that the travel of all of the devices is relatively continuous.

Although I have herein shown and described one embodiment of my invention, manifestly it is capable of substantial modifications and rearrangement of parts without departing from the spirit and scope thereof. I do not, therefore, wish to be understood as limiting this invention to the precise form herein shown and described, except as I may be so limited by the appended claims.

I claim:

1. A chainless conveyer, comprising in combination guide means for the upper and lower runs of the conveyer including a pair of vertically spaced apart guide tracks at each side of the conveyer and curved end track members disposed in registration with each end of each pair of guide tracks, a plurality of independent, material supporting devices each having a plurality of rollers at each side thereof mounted for support on and movement over said guide tracks with one roller of each side engaging the corresponding curved end member, each of said devices being adapted to abut against the next adjacent device for imparting movement from one to another, and means for sequentially engaging the respective devices individually for moving the same from one run of the conveyer to the other run into abutting engagement with the previously moved device for imparting movement to all of the devices on said other run of the conveyer, the adjacent portions of consecutive devices being provided with cooperating abutment features and one set of said features on each device being adjustable relatively to said each device to insure proper spacing of said devices.

2. A chainless conveyer, comprising in combination guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a plurality of horizontally spaced apart rollers at each side thereof mounted for support on and movement over said guide tracks with one roller of each side adapted for engaging the corresponding curved end member, each of said devices being adapted to abut against the next adjacent device for imparting movement from one to another, and means for sequentially

engaging two of said horizontally spaced apart rollers at each side of the respective devices while said one rollers at each side engage the curved end member for moving the devices individually in a substantially horizontally disposed position from one run of the conveyer to the other run into abutting engagement with the previously moved device for imparting movement to all of the devices on said other run of the conveyer.

3. A chainless conveyer, comprising in combination guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a plurality of horizontally spaced apart rollers at each side thereof mounted for support on and movement over said guide tracks with one roller of each side adapted for engaging the corresponding curved end member, each of said devices being adapted to abut against the next adjacent device for imparting movement from one to another, each of said devices including a frame and a material supporting tray element removably mounted on said frame, and means for sequentially engaging two of said horizontally spaced apart rollers at each side of the respective devices while said one rollers at each side engage the curved end member for moving the devices individually in a substantially horizontally disposed position from one run of the conveyer to the other run into abutting engagement with the previously moved device for imparting movement to all of the devices on said other run of the conveyer.

4. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and means at one end of the conveyer for sequentially engaging the respective devices individually, adjacent opposite ends thereof, for moving the same in a substantially horizontally disposed position from one run of the conveyer to the other run, with the rollers at the leading edge of each device engaging and riding over the corresponding end track members, and causing each device to abut the previously moved device for imparting movement to all of the devices on said other run of the conveyer.

5. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and means at one end of the conveyer for sequentially engaging the respective devices individually, adjacent opposite ends thereof, for moving the same in a substantially horizontally disposed position from one

run of the conveyer to the other run, with the rollers at the leading edge of each device engaging and riding over the corresponding end track members, and causing each device to abut the previously moved device for imparting movement to all of the devices on said other run of the conveyer, said means being constructed and arranged to impart motion to said devices in a manner to effect continuous movement of all of said devices as a unit.

6. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at opposite ends of the conveyer for sequentially engaging the respective devices individually, adjacent opposite ends thereof, for moving the same in a substantially horizontally disposed position from one run of the conveyer to the other run, with the rollers at the leading edge of each device engaging and riding over the corresponding end track members, and causing each device to abut the previously moved device for imparting movement to all of the devices on said other run of the conveyer.

7. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at opposite ends of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device for imparting movement to all of the devices on said other run of the conveyer, one of said means being power driven and the other being operated by the motion of said devices.

8. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut

the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends 10 of said devices for moving said devices from one run of the conveyer to the other.

9. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends 25 of said devices for moving said devices from one run of the conveyer to the other.

15 30 35 40 45

10. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated 55 60 65 70 75

as to simultaneously engage the end rollers at the opposite ends of said devices for moving said devices from one run of the conveyer to the other, said auxiliary sprockets each being axially offset outwardly relatively to the adjacent main sprocket to insure clearance for the intermediate rollers on the adjacent end of said devices, and said end rollers at each end of each device being composed of two axially aligned independently movable rollers so as to permit engagement of the outermost roller with the auxiliary sprockets and to afford free rolling support for one end of the device upon final stage of transfer movement.

11. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends of said devices for moving said devices from one run of the conveyer to the other, said auxiliary sprockets each being axially offset outwardly relatively to the adjacent main sprocket and each being mounted on separate stub shafts to insure clearance for the intermediate rollers on the adjacent end of said devices, and said end rollers at each end of each device being of such length as to permit engagement with said auxiliary sprockets.

12. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and aux-

iliary sprocket wheels at each side of the conveyer, the corresponding sprockets of the respective pairs being aligned and said main and auxiliary sprockets being so correlated as to simultaneously engage the end rollers at the opposite ends of said devices for moving said devices from one run of the conveyer to the other, each pair of aligned main sprockets being mounted on an operating shaft, and the auxiliary sprockets each being axially offset outwardly relatively to the adjacent main sprocket and each being mounted on separate stub shafts to insure clearance for intermediate rollers on the adjacent ends of said devices, and the end rollers of each group at each end of each device being dimensioned for cooperative engagement with the auxiliary sprockets.

13. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends of said devices for moving said devices from one run of the conveyer to the other, each pair of aligned main sprockets being mounted on an operating shaft, and the auxiliary sprockets each being axially offset outwardly relatively to the adjacent main sprocket and each being mounted on separate stub shafts to insure clearance for intermediate rollers on the adjacent ends of said devices, and the end rollers of each group at each end of each device being dimensioned for cooperative engagement with the auxiliary sprockets.

14. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially en-

gaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends of said devices for moving said devices from one run of the conveyer to the other, said auxiliary sprockets each being axially offset outwardly relatively to the adjacent main sprocket to insure clearance for the intermediate rollers on the adjacent end of said devices, and said end rollers at each end of each device being composed of two axially aligned independently movable rollers so as to permit engagement of the outermost roller with the auxiliary sprockets and to afford free rolling support for one end of the device upon final stage of transfer movement, and separate control means associated with the guide means adjacent each cooperating pair of main and auxiliary sprockets, each of said control means including a part actuated by the outermost roller at the leading edge of each device for controlling movement of the opposite edge of each device during movement thereof from one run of the conveyer to the other.

15. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends of said devices for moving said devices from one run of the conveyer to the other, said auxiliary sprockets each being axially offset outwardly relatively to the adjacent main sprocket to insure clearance for the intermediate rollers on the adjacent end of said devices, and said end rollers at each end of each device being composed of two axially aligned independently movable

rollers so as to permit engagement of the outermost roller with the auxiliary sprockets and to afford free rolling support for one end of the device upon final stage of transfer movement, and separate control means associated with the guide means adjacent each cooperating pair of main and auxiliary sprockets, each of said control means including an operating cam disposed adjacent the main sprocket and a control arm engageable by the outermost roller at the leading edge of each device for moving said cam into cooperating position relatively to the outermost roller at the other edge of said devices for insuring maintenance of said devices in horizontal position during initial stage of transfer from the upper run to the lower run.

20. A chainless conveyer, comprising in combination, guide means for the upper and lower runs of the conveyer including a pair of vertically spaced apart guide tracks at each side of the conveyer and curved end track members disposed in registration with each end of each pair of guide tracks, a plurality of independent, horizontally traveling material supporting devices each having a frame and a plurality of aligned, horizontally spaced apart rollers at each side of the frame adapted for support on and movement over said guide tracks, and transferring means at each end of the conveyer for sequentially engaging the respective devices individually for moving the same in a substantially horizontally disposed position from one run of the conveyer to the other run, with the rollers at the leading edge of each device engaging and riding over the corresponding end track members, and causing each device to abut the previously moved device in a manner to effect continuous movement of all the devices on said other run of the conveyer, each transfer means comprising a pair of endwise offset main and auxiliary sprocket wheels at each side of the conveyer, the corresponding sprockets of the respective pairs being aligned and said main and auxiliary sprockets being so correlated as to simultaneously engage the end rollers at the opposite ends of said devices for moving said devices from one run of the conveyer to the other, said auxiliary sprockets each being axially offset outwardly relatively to the adjacent main sprocket to insure clearance for the intermediate rollers on the adjacent end of said devices, and said end rollers at each end of each device being composed of two axially aligned independently movable rollers so as to permit engagement of the outermost roller with the auxiliary sprockets and to afford free rolling support for one end of the device upon final stage of transfer movement, and separate control means associated with the guide means adjacent each cooperating pair of main and auxiliary sprockets, each of said control means including an operating cam disposed adjacent the main sprocket and a control arm engageable by the outermost roller at the leading edge of each device for moving said cam into cooperating position relatively to the outermost roller at the other edge of said devices for insuring maintenance of said devices in horizontal position during initial stage of transfer from the upper run to the lower run, said cam having an operating surface corresponding in contour to a similar portion of the adjacent curved end track member.

HERMAN SEUBERT.
